GOLF CLUB

Clifford Lussky and Mortimer W. Brumleve,
Louisville, Ky.

Application August 1, 1932, Serial No. 627,190

3 Claims. (Cl. 273—81)

Our invention consists in new and useful improvements in golf clubs and relates more particularly to the handle or gripping member of the golf club shaft, having for its object to provide what might be termed a double grip consisting of a right and left hand gripping portion, each of which is shaped to accommodate the respective hand of the golfer in the proper gripping position only. That is, we have designed a handle which will automatically adjust itself and the hands of the golfer into the proper relative positions.

As the result of the inherent tendency of the human body to seek co-ordination of the various members of the body so as to obtain a maximum of rhythm with a minimum of effort in the execution of a golf stroke, there has been a decided improvement in the manner in which the game of golf is played. This improvement has not alone been directed to the proper movement of the elements of the body but to the material and structure of the ball, the golf club head, the shaft and the grip.

Although efforts have been made to devise golf club grips which will facilitate the proper handling of the club, little has actually been accomplished to assist the novice who is undertaking to learn the game of golf.

We are familiar with a number of these former efforts which, for example, consist of grips which have been constructed with a series of grooves for the fingers of each hand and an indentation for the thumbs. Others have cut out portions of a normally round handle leaving angularly disposed grips for engagement by the hands, and still others have provided finger loops which are secured to the handles for receiving the fingers and thumbs of the player.

However all of these devices have failed to definitely and accurately fix the grip of the golfer so as to insure the proper relative positions of the hands with respect to one another to bring the face of the club up to the ball at the proper angle to effect a straight and accurate drive to the point of destination. One reason for the failure of a number of these devices has been that they were designed at a time prior to the modern development of the manner in which the game is played.

Our improved grip is so designed as to bring about in the very beginning a back-swing with a straight arm. By reason of the structure and shape of the gripping portions, the only comfortable positions which the hands can assume is the proper position for the correct relative loca-

tion and movement of the hands of the golfer. It is a generally accepted theory in golf that if the back-swing is correct, the stroke must necessarily finish properly. Consequently, we have designed a grip whereby the wrist automatically cocks itself, the thumbs and forefingers being so placed as to get the maximum of power in the down-stroke. Once the down-stroke is in motion, the forward hand accommodates itself immediately, both at the point of contact and in the follow-through. The forefinger of the forward hand exerts a maximum of power when the club reaches the ball.

In other words, the fundamental purpose of our invention is to produce a grip which will automatically cause the fingers, the thumbs, the wrists and the fore-arms to work in harmony and to cause the golfer to unmindfully grasp the club with the modern interlocking grip which is now generally accepted to be the proper method of holding a golf club.

With the above and other objects in view which will appear as the description proceeds, our invention consists in the novel features herein set forth, illustrated in the accompanying drawing and more particularly pointed out in the appended claims.

Referring to the drawing in which numerals of like character designate similar parts throughout the several views,

Fig. 1 is a view in front elevation showing the relative angular location of the two gripping portions with respect to one another and to the face of the head of the golf club.

Fig. 2 is a similar view in side elevation looking from a point in line with the face of the head of the club.

Fig. 3 is a rear view of the gripping members.

Fig. 4 is a side elevation of the gripping portions from the reverse side of Fig. 2.

Fig. 5 is an end view taken on line 5—5 of Fig. 1.

Fig. 6 is a transverse sectional view taken on line 6—6 of Fig. 1.

Fig. 7 is a similar view taken on line 7—7 of Fig. 1.

Fig. 8 is a transverse sectional view taken on line 8—8 of Fig. 1, and

Fig. 9 is a perspective view illustrating the positions of a golfer's hands in grasping our improved handle with an interlocking grip.

In the drawing, 1 represents the shaft of a golf club which may be constructed of any suitable material and having at its lower extremity a conventional head 2 having a ball-engaging face 3. The opposite end of the shaft 1 terminates in our

improved double grip or handle 4 which may be formed integral with the shaft or secured thereto in any suitable manner. The handle 4 may be composed of wood and properly shaped either by hand or an automatic lathe or it may be cast from any suitable material or compositions of materials.

This double grip handle consists of two gripping portions 5 and 6, the former terminating at one end toward the head of the club in an enlarged 10 knob 7 which gradually tapers rearwardly into a reduced neck portion 8 adapted to accommodate the thumb and forefinger of the forward hand of the golfer. It will be noted from Figs. 1, 2 and 9 that this neck portion 8 is indented as at 8' for 15 the specific accommodation of the thumb while Figs. 3 and 4 show an indentation 8^b on the opposite side to accommodate the arched forefinger of the forward hand.

The neck portion 8 merges rearwardly into a 20 gradually enlarged body portion 9 which bulges outwardly and is substantially oval in cross section, said body 9 being adapted to accommodate and fill the encircling area of the remaining gripping fingers of the forward hand. The body portion 9 is gradually reduced towards its rear extremity and terminates in a second neck portion 25 10 for accommodating the thumb and forefinger of the rearmost hand of the golfer. As will be seen from Figs. 1, 2 and 9, the neck 10 is indented as at 10' to receive the thumb and the rearmost hand, and referring to Figs. 3 and 4, said neck is indented as at 10^b to accommodate the arched forefinger of the rearmost hand.

The second neck 10 merges rearwardly into a 30 second gradually enlarged body 11, the latter being substantially oval in cross section and bulging outwardly as in the case of the body portion 9. However said body portion 11 is arranged at a 35 slight angle with respect to the body portion 9 as will be seen by a comparison of the sectional views 40 shown in Figs. 7 and 8, the purpose of such angular disposition being to properly adjust the hands of the golfer to the proper relative gripping position for the interlocking grip.

The second body 11 terminates rearwardly in a 45 reduced portion 12 for receiving the little finger of the rearmost hand and from thence the handle flares outwardly to the rear end of the club as at 13, said flaring portion being adapted to engage 50 adjacent the heel of the rearmost hand of the golfer.

It will be noted, particularly in Fig. 1, that the gripping portions 5 and 6 are arranged at a decided angle to the face of the golf club head, said 55 angle being such, in the case of each gripping portion, that when the hands are in the proper positions, as shown in Fig. 9, the face of the head 2 will contact with the ball at an angle which is 60 normal to a straight line drawn between the ball and the point of destination.

In constructing our improved golf clubs it is of the utmost importance to attach the head 2 at the proper angle, for the function of the club depends entirely upon the relative positions of the 65 hands with respect to one another and with respect to the head of the club, and the position of the latter with respect to the ball in approaching the same for contact.

Thus with a golf club constructed in accordance 70 with our invention, the primary obstacle of the novice is eliminated and even in the case of an experienced golfer, the proper gripping of the club is facilitated.

While we have shown in the drawing our 75 proved golf club handle as applied to a driver, it

is obvious that the principle of our invention may be readily applied to other golf clubs such as brassie, spoon, long and short irons, and the putter, with equal effect. In fact it is our intention to equip a complete set of golf clubs with 80 handles or gripping members such as described in the foregoing.

It will be noted that with a grip constructed in accordance with our invention no sheepskin or other wrapping is necessary as the peculiar curvature of the gripping portions so fill the encircling hands of the golfer as to facilitate a positive, firm grip which eliminates slipping of the hands. Of course it may be desirable in some instances to employ a suitable wrapping or cover but such wrapping or cover should and must conform to the external shape and curvature hereinbefore described.

Furthermore, our invention contemplates a grip 95 constructed in accordance with our invention which may be of an auxiliary nature and adaptable for application to clubs of conventional structure. In such instances it would be essential to line the gripping member up to the proper angle with the face of the club head and to provide means for positively locking such gripping member in place, such for example as transverse pins extending through the gripping member and shaft.

From the foregoing it is believed that the objects and advantages of our invention may be 105 readily understood by those skilled in the art without further description, it being borne in mind that numerous changes may be made in the details of construction without departing from the spirit of the invention as set forth in the following claims.

What we claim and desire to secure by Letters Patent is:—

1. In a golf club, a handle comprising two co- 115 axial gripping portions, substantially oval in cross section, each of said gripping portions being reduced at its longitudinal extremities and gradually bulging towards its longitudinal center, said gripping portions being arranged at a transverse 120 angle with respect to the face of the head of said golf club and at a slight angle with respect to one another, to insure the proper relative positions of the hands of a golfer with respect to one another and to the face of the club. 125

2. In a golf club, a handle comprising two gripping portions, one of said gripping portions terminating at one end toward the head of the club in an enlarged knob which gradually tapers rearwardly into a reduced neck portion to accommodate the thumb and forefinger of the forward hand of the golfer, said neck portion merging rearwardly into a gradually enlarged body which is substantially oval in cross section, said body being adapted to accommodate the remaining 130 gripping fingers of the forward hand, said body portion being gradually reduced towards the rear extremity of the handle and terminating in a second neck for accommodating the thumb and forefinger of the rear hand, said second neck gradually merging into a second enlarged body, the latter being substantially oval in cross section and arranged at a slight angle with respect to the first body, said second body terminating in a reduced portion for receiving the little finger 135 of the rear hand, and from thence flaring to the rear end of the club into a portion adapted to engage the heel of the rearward hand of the golfer, both of said bodies being arranged at an angle to the face of the club. 140 145 150

3. A gripping handle for a golf club terminating at its ends in enlarged portions and having intermediate said enlarged portions two neck portions, one of said neck portions, the lower enlarged portion and the space between the two neck portions being adapted to be engaged by the thumb and forefinger and the remaining gripping fingers of the leading hand of the golfer, and the second neck portion, the space between said portion and the enlarged outer end, and the said enlarged outer end being adapted to be engaged by the thumb, forefinger, the other gripping fingers and the heel of the other hand. 80
